CHAIR FRAME STRUCTURE

Herbert V. Thaden, High Point, N.C., assignor, by mesne assignments, to Samuel S. Dennis 3rd, Boston, Mass., trustee

Filed Nov. 26, 1958, Ser. No. 776,625

4 Claims. (Cl. 287—54)

This invention relates generally to a novel metal chair frame structure and more particularly to a chair frame provided with reinforcing rod and pipe joint coupling means. The invention also relates to novel clamping means for securing a plurality of adjacent chairs together in rows.

In so-called stack chairs having tubular metallic frames the problem arises of providing means for securing the transverse rods or tubular members to the tubular leg elements. It is customary in the art to weld the transverse rods or tubular members to the leg elements or to connect the same by removable fastener means, such as metal screws, nuts and bolts and the like. The present invention was developed to provide novel readily-assembled rod joint coupling means for connecting the elements together in a simple, rigid reinforcing manner without necessitating the use of weld seams or other connections.

The primary object of my invention is to provide an extremely rigid chair frame structure having split sleeve coupling means for connecting the transverse cylindrical members to the tubular chair leg elements.

Another object of my invention is to provide a chair row assembly consisting of a plurality of chairs each having U-shaped bent tubular members the extremities of which define chair legs, in combination with novel clamping means for connecting the adjacent legs of adjacent chairs together in a rigid manner.

A more specific object of my invention is to provide a chair frame structure having two bent U-shaped tubular elements the extremities of which define pairs of hollow chair legs and also having split sleeve means within said hollow legs for firmly connecting the ends of transverse cylindrical bracing members within the legs.

Still another object of my invention is to provide a novel pipe joint coupling consisting of a first cylindrical member inserted transversely through at least one peripheral opening in a hollow second tubular member, and a split sleeve member colinearly arranged within said hollow second member, one side of said split sleeve member cooperating with a peripheral notch in said first cylindrical member to secure said first member to said second member.

A further object of my invention is to provide a clamp for connecting the adjacent inclined legs of two chairs together, said clamp having oppositely extending bent projections at both ends thereof for engaging said legs to prevent lateral movement of the chairs relative to each other.

Another object of my invention is to provide means for clamping together the leg bracing rods of two adjacent chairs and thus prevent relative lateral movement of the chairs.

Other objects and advantages of my invention will become more apparent from a study of the following specification when considered in conjunction with the accompanying drawings in which:

2

Fig. 1 is a perspective exploded view of a chair embodying my novel tube and rod joint coupling;

Fig. 2 is a transverse sectional view of the rod joint coupling taken along line 2—2 of Fig. 3;

Fig. 3 is a vertical section of the rod joint taken along line 3—3 of Fig. 2;

Fig. 4 is a front elevational view of a plurality of chairs ganged together by means of my novel connecting clamp;

Fig. 5 is a detailed sectional view of the connecting clamp taken along line 5—5 of Fig. 4;

Fig. 6 is a detailed sectional view of another embodiment of my connecting clamp;

Fig. 7 is a side elevational view of a plurality of chairs connected by the clamp of Fig. 6;

Fig. 8 is a sectional plan view of a joint similar to that of Fig. 2 wherein both elements are tubular;

Figs. 9 and 10 are sectional plan and elevational view, respectively, of a split sleeve joint embodiment for connecting two angularly-arranged cylindrical members to a main tubular member;

Figs. 11 and 12 are perspective and detailed views of another embodiment of chair clamping means; and

Fig. 13 is a perspective view of still another chair clamping embodiment of my invention.

Referring now more particularly to Figs. 1—3, the chair frame 1 consists of a pair of bent U-shaped tubular elements 2, 3 the extremities of which define the four chair legs 4, 5, 6 and 7. As will be explained below, the hollow tubular elements may be made of light gage aluminum, light weight steel or other suitable structural material.

The tubular elements 2 and 3 are connected by means rigid transverse rods 8, 9, 10 and 11. While for the purpose of the present description the transverse elements 8—11 have been illustrated as being solid rods, it is apparent that the joint described below may be made in the same manner if the elements 8—11 are tubular. Rods 8 and 9 and rods 10 and 11 are connected at their central portions, respectively, by means of the weld seams 12, by means of sleeves, or by any other suitable connecting means. The rigid seat unit 13 having a back portion 14 is supported by the transverse rods 8 and 10 and is secured thereto by suitable securing means (not shown). At their lower extremities the legs are provided with relatively soft protective elements 15 which prevent scratching and marring of the floor surface.

It is to be noted that legs 4 and 5 and legs 6 and 7, respectively, are angularly inclined at acute angles with respect to each other. Stability and rigidity is provided to the legs by the transverse bracing bars 16 and 17 having notches 18 therein for receiving the rods 8 and 19 of the next lower chair when a plurality of chairs are stacked upon each other in a nested fashion.

According to the present invention, novel rod joint means are provided for connecting the ends of rods 8, 9, 10 and 11 to the tubular legs 4, 5, 6 and 7. Referring now to Figs. 2 and 3 (which disclose the joint as applied to leg 5) the extremities of rods 10 and 11 extend through apertures 5a and 5b in the tubular legs 5. The rods have vertical side notches 10a, 11a in those portions thereof which extend within the tubular leg. The vertical notches are in the peripheral walls of the rods immediately adjacent the inner periphery of the tubular leg.

The extremities of the rods 10 and 11 are secured within the tubular leg 5 by means of the longitudinally-split sleeve member 19 which is driven upwardly within the hollow leg 5 by suitable mandrel means during assembly of the chair frame. The vertical side portion 19a of the split flange 19 is inserted within the vertically aligned notches 10a, 11a of the rods 10 and 11 to rigidly lock the rod ends within the hollow leg 5 and thus

prevent longitudinal movement of the rods. It should be mentioned that the outer diameter of the sleeve 19 is substantially equal to the inner diameter of the hollow leg 5. Also, for a tight fit of the assembled elements it is desirable that the gap between the side portions 19a and 19b of the split sleeve be approximately equal to the transverse thickness of the rods at the notched portions thereof. The sleeve 19 is preferably formed from steel or other suitable metal possessing relatively great inherent strength.

In a similar manner, split sleeves 20, 21 and 22 (Fig. 1) serve to secure the ends of the rods within the hollow legs 4, 6 and 7, respectively.

It is important to note that not only do the split sleeves 19, 20, 21 and 22 serve to lock the ends of the rods within the hollow legs but also the sleeves serve to reinforce the hollow legs at the point of rod junctures. Should the tubular elements 2 and 3 be formed of light gage aluminum, for example, the length of the split sleeves may be extended if desired so that the lower ends of the sleeves terminate adjacent the ends of the hollow legs and thus serve to reinforce the legs over the better portion of their length.

It will be readily apparent that many advantages are achieved from the use of a chair structure having the novel rod and pipe joint structure according to the present invention. First, the chair frame components may be shipped in a knocked-down disassembled state to reduce shipping space and costs, the chair frame being readily assembled by the retailer without the necessity of weld joints or the like. Also, by the use of the inexpensive steel split locking and reinforcing sleeves, low strength decorative tubing (such as anodized aluminum, for example) may readily be used for the bent U-shaped elements 2 and 3.

Referring now to Figs. 4-7, clamping means are illustrated for connecting as a rigid assemblage a plurality of the stack chairs of Fig. 1 arranged in a row. As shown in Figs. 4 and 5 the chairs are arranged side by side and the adjacent legs of the chairs are joined by means of the clamps 30. As shown in Fig. 5 the clamp 30 consists of a rigid upper rod 31 having horizontal bent portions 31a, 31b at each end thereof and a rigid lower rod 32 having horizontal bent portions 32a, 32b at each end thereof, the bent portions of rod 32 extending outwardly in the opposite direction from the bent portions of rod 31. Rods 30 and 31 are connected at their longitudinal central portions by means of a weld seam or other suitable connection. In order to clamp the legs of adjacent chairs together, the clamp 30 is inserted intermediate the upper bent portions of the U-shaped element 2 of one chair and the U-shaped element 3 of the adjacent chair and is moved downwardly until bent portions 31a and 31b of rod 31 engage the angularly-inclined legs 5 and 4, respectively, and bent portions 32a and 32b engage angularly-inclined legs 7 and 6, respectively. The clamp 30 thus is maintained in position between the chairs and firmly prevents relative movement of the chairs in any horizontal direction.

According to the clamp embodiment of Figs. 6 and 7, the rods 33, 34 having bent end portions 33a, 33b, 34a, and 34b are slidably connected by means of collars 35 which encircle the straight central portions of the clamp. By means of this clamp embodiment the chairs of Fig. 7 may be moved forwardly or rearwardly with respect to each other to a certain extent to achieve a staggered seating arrangement as desired in various installations. The clamp will prevent lateral displacement of the chairs relative to each other.

Fig. 8 is a cross-sectional view similar to that of Fig. 2 wherein the transverse cylindrical member 40 is tubular as well as the main hollow member 41. Split sleeve 42 has a portion 42' which extends into the transverse

peripheral slot 40' to retain the end of tubular member 40 within the bore of hollow member 41.

As shown in Figs. 9 and 10, a plurality of angularly-arranged transverse rods 44, 45 may be secured to the main hollow member 46 by means of a sleeve 47 having axial slots 48, 49, 50 in cooperative engagement with grooves 45', 44', 44" to secure the rods to member 46. It will be noted that rod 44 extends completely through oppositely aligned apertures in the main hollow member 46. Instead of providing the axial slots in sleeve 47, the sleeve may be subdivided into a plurality of sections if desired.

Figs. 11 and 12 disclose an alternative embodiment of clamping means for joining together the legs of two adjacent chairs. The generally U-shaped clamp 60 is pivotally connected at its extremities to the transverse rod 61 and has a laterally-bent central portion 60' adapted to removably engage the transverse bracing rod 62' to clamp the two chairs together. While the portion 60' has been illustrated as extending upwardly in Fig. 12 (the clamp 60 being adapted for counterclockwise pivotal movement to cause clamping engagement), it will be apparent that as an alternative the bent portion 60' could extend downwardly so that clamping engagement would be achieved by clockwise pivotal movement of clamp 60.

Fig. 13 illustrates another embodiment of a clamp similar to that of Fig. 5 wherein the longitudinal member consists of two pivotally connected sections 70, 71 each having lateral projections 72 with downwardly-bent extremities 73. In order to clamp together a pair of the chairs illustrated in Fig. 1, the clamp is jack-knifed about its central pivot 74 and is inserted between the adjacent chair legs. The sections 70, 71 are then pivoted to a horizontal position so that the projections 72, 73 will connect the bracing rod 16 of one chair with the bracing rod 17 of the adjacent chair and thus connect the chairs together to prevent relative lateral motion therebetween.

While in accordance with the patent statutes I have illustrated and described the best forms and embodiments of my invention now known to me, it will be apparent to those skilled in the art that other changes and modifications may be made in the apparatus described without deviating from the scope of the invention as set forth in the following claims.

I claim:

1. A rod and pipe joint coupling comprising a hollow first tubular member having an opening in the periphery thereof, a second cylindrical member arranged at an angle with respect to said first tubular member, one end of said second member extending through the apertures of said first member and terminating within said first member, the portion of said second member extending within said hollow first member having a peripheral groove therein, and a split cylindrical sleeve coaxially arranged within said hollow first member, a portion of said sleeve extending within the peripheral groove of said second member to connect said second member to said first member.
2. A coupling as defined in claim 1 wherein said second cylindrical member is tubular.
3. A rod and pipe joint coupling comprising a hollow first tubular member having a pair of oppositely-aligned openings in the periphery thereof, a second cylindrical member arranged at an angle with respect to said first tubular member and extending through said openings, the portion of said second member within said hollow first member having a pair of peripheral grooves therein and a cylindrical sleeve coaxially arranged within said hollow first member, said sleeve having a plurality of axially-extending slots at one end thereof, the walls of said slots extending within the peripheral grooves of said second member to connect said second member to said first member.

4. A rod and pipe joint coupling comprising a tubular first member, at least two second cylindrical members angularly-arranged with respect to each other, one end of each of said second cylindrical members extending through peripheral openings in said first member, the portions of each of said second members within said first member having at least one peripheral groove therein, and a cylindrical sleeve coaxially arranged within said hollow first member, said sleeve having a plurality of axially-extending slots at one end thereof, the walls of said slots extending within the peripheral grooves of said second members to connect said second members to said first member.
